[57] CLAIM

The ornamental design for a case for a radio or the like,
as shown and described.

DESCRIPTION

FIG. 1 is a front elevational view of a case for a radio or
the like showing my new design;

FIG. 2 is a top plan view thereof;

FIG. 3 is a rear elevational view thereof;

FIG. 4 is a right side elevational view thereof, the left
side being a mirror image; and

FIG. 5 is a bottom plan view thereof.
